SIGNALING SYSTEM FOR RAILROADS

Joseph E. Willing, Rochester, N. Y., assignor to
General Railway Signal Company, Rochester,
N. Y.

Original application February 17, 1932, Serial No.
593,549. Divided and this application January
22, 1937, Serial No. 121,845

1 Claim. (Cl. 175--320)

This invention relates to absolute-permissive-block signaling systems for railroads, and more particularly to such a system employing direct current polarized home-distant relays of an improved type.

The present application is a division of my prior application Ser. No. 593,549, filed February 17, 1932, for Signaling system for railroads, now Patent 2,072,232, granted March 2, 1937.

10 An absolute-permissive-block signaling system is a system in which a single track section is signaled for traffic moving in either direction, and a system which affords the same protection and facility for trains following each other through 15 the single track section as is afforded in modern signaling systems for tracks signaled for one direction of traffic only, and in which an opposing train is prevented from entering a single track section already occupied by a train or trains. 20 This facility of train signaling is accomplished by connecting the various home-distant relays for each direction of travel in tumble-down or repeater fashion, so that the deenergization of one relay causes the next relay in the rear to be deenergized, and so on through the entire track section, and in which a directional relay, such as a stick 25 relay, is employed for closing an auxiliary circuit to the next home-distant relay in the rear of a signal at stop, completed in response to the movement of a train in the proper direction.

30 In signaling systems of the type mentioned, the home-distant relay should be slow to pick up, in order to prevent the false or improper picking up of a directional stick relay, and such home-distant relay should be slow to drop, so that the directional stick relay can be picked up under certain traffic conditions.

35 In accordance with the present invention it is proposed to use a polar neutral relay, as such home-distant relay, wherein a short circuited winding 40 of low resistance or usual copper bank is provided for making the relay slow to release its neutral armature.

45 It is further proposed to include a resistance in series with the main winding of such home-distant relay, which resistance is short-circuited when the relay assumes its attracted position, in order to render such relay slow to pick up, but after being picked up, saturates the main magnetic circuit so as to induce a heavy current in the short circuited winding, to make it slow dropping.

50 Another function performed by home-distant relays of this type is that upon pole changing of the main circuit for the relay, the neutral ar-

ture of such relay will be only momentarily de-energized whereby the slow action of subsequent home-distant relays prevents what is known in signal parlance as a kick-off, which consists in momentary sequential deenergization of a series of home relays, this by reason of momentary de-energization of the first of these relays due to pole changing of its energizing circuit.

55 Other objects, purposes and characteristic features of the present invention will in part be obvious from the accompanying drawing and will in part be more fully described hereinafter.

60 In describing the invention in detail reference will be made to the accompanying drawing, which shows one embodiment of the invention applied 15 to a portion of a single track section of a railway.

65 Referring to the drawing, the track rails 1 have been shown divided into blocks by insulating joints 2, of which the block I and the adjacent 20 ends of two other blocks H and J only have been shown, and in which each block is further divided by insulating joints 3 to constitute a divided block having two track circuited sections each provided with a track circuit including a battery 25 B (containing a suitable exponent) and a track relay T (containing a suitable exponent). At the entrance end to each block, for each direction of traffic, has been shown a light signal S (containing 30 a proper exponent) of which the east-bound signals have been designated S⁴ and S⁶ and the west-bound signals have been designated S³ and S⁵.

70 Since each of these signals is controlled in exactly the same way it will suffice to describe the control circuits for the signal S⁴, like parts for controlling other signals being designated by reference characters having distinctive exponents. The signal S⁴ is controlled by home-distant relay HD⁴ and a track relay T³, a back contact of the 75 directional stick relay 5S being included in the 40 energizing circuit for the home-distant relay HD⁴, for checking purposes. The home-distant relays for the signals S³ and S⁵ and the associated circuits have for convenience been omitted but are the same as those of S⁶ and S⁴, respectively. It is believed that the invention is most readily understood by considering the operation of the system as effected by the movement of trains.

Operation

50

Under normal clear traffic conditions, the home-distant relay HD⁴ is energized through the following circuit:—beginning at the terminal (B+) of a suitable battery having its mid-point 55

- connected to the common return wire C, front contact 19 of relay HD⁶, wires 11 and 13, back contact 14 of the stick relay 6S, wire 15, front contact 16 of the track relay T⁵, wire 17, back contact 18 of the opposing directional stick relay 6S, wire 19, front contact 20 of the track relay T⁴, wire 21, main winding of the relay HD⁴, wire 22, resistance unit R⁴, wires 23, 24, 25, C, 25¹ and 26¹ to the mid-point of said battery.
- 10 Let us first assume that a west-bound train, that is a train moving from right to left, is entering the block J. The entrance of this train will result in opening of the contact 16¹ (not shown) of the track relay T⁷ (not shown) thereby deenergizing the home-distant relay HD⁶. Dropping of the home-distant relay HD⁶ will result in opening of its contact 18, thereby illuminating the danger aspect of signal S⁶ by lighting of the red lamp R. Further, opening of the contact 18 of the relay HD⁶ will break the energizing circuit for the home-distant relay HD⁴, heretofore traced, and this relay HD⁴ will in the same way deenergize the relay HD² (not shown) in the rear thereof. This sequential deenergization of the 25 home relays HD⁰, HD⁴, etc., is known as the tumble-down function, which blocks opposing trains, and prevents their entering a single track section already occupied by the train.
- As the train in question passes the signals S⁵ 30 and S³ these signals will indicate traffic conditions in advance, and will indicate traffic conditions to other following trains, all in a manner as will be described hereinafter in connection with the operation of signals S⁴ and S⁶.
- 35 Let us now assume that an east-bound train, moving from left to right enters the block H. The entering of this train into the block H will result in tumbling down of the home relays for the signals S³ and S⁵, so that these signals S³ and S⁵ will assume their stop condition. As soon as this train in the block H passes into the second track circuit thereof containing the track relay T³, it will cause dropping of this track relay T³ and opening of its contact 16⁰. At this time, 40 assuming the existence of clear traffic conditions in advance for east-bound trains, there is completed the following energizing circuit for the green lamp G: beginning at the terminal (B+) of a suitable battery, front contact 10⁰ of the relay HD⁴, wires 11⁰ and 12⁰, polar contact 31⁰ assuming its right-hand position, wire 32, green lamp G of the signal S⁴ to the common return wire C connected to the mid-point of said battery.
- 45 Let us now assume that the train in question passes the signal S⁴. In so doing it effects deenergization of the track relay T⁴. Dropping of the contact 20 of the track relay T⁴ breaks the energizing circuit for the relay HD⁴, but the rapid dying of flux in the main core structure of the relay HD⁴ causes a voltage to be induced in the secondary winding or slug 60 of this relay, thereby causing current to flow therein and hold HD⁴ up for a short time, and since the relays S are 50 built to be quick acting, this period of time is sufficient for the directional stick relay 6S to be picked up through the following pick-up circuit: beginning at the terminal (B+), back contact 40 of the track relay T⁴, wires 41 and 42, front contact 43 of the relay HD⁴, wires 44 and 45, winding of the stick relay 6S, to the common return wire C connected to the mid-point of the local battery.
- 55 Closure of this circuit picks up the stick relay 75 6S, which immediately upon closure of its stick

contact 47 will close the following stick circuit: beginning at the terminal (B+) of the local battery, back contact 49 of the track relay T⁴, wires 44 and 48, stick contact 47 of the relay 6S, wires 43 and 45, winding of the relay 6S to the common return wire C. Immediately upon dropping of the relay HD⁴ an auxiliary stick circuit for the relay 6S is closed, which may readily be traced, and includes the back contact 43 of the relay HD⁴ and the stick contact 47 of the relay 6S. 10

As soon as the east-bound train has passed entirely out of the block H, the contact 16⁰ of the track relay T³ will be closed, thereby closing a caution circuit for the next home-distant relay in the rear, this caution circuit leading from the 15 terminal (B-), through front contact 14⁰ of the stick relay 6S, wire 15⁰, front contact 16⁰ of the track relay T³, wire 17⁰, back contact 18⁰ of the stick relay 6S, line wire 19⁰, etc.

Let us now assume that the east-bound train in question passes through the block I and enters the block J. This train will of course, assuming traffic conditions in advance to be favorable, find the signal lamp G of the signal S⁶ energized when it reaches this signal S⁶, all in a manner as already explained in connection with the signal S⁴. As this east-bound train enters the block J and deenergizes the track relay T⁶, it will pick up the directional stick relay 6S, in a manner as already pointed out in connection with the directional stick relay 6S. 20

As the rear end of the train passes entirely out of the block I, the home-distant relay HD⁴, which was deenergized during the entire occupancy of the block I is now energized to its left-hand position through the following caution circuit: beginning at the terminal (B-), front contact 14 of the directional stick relay 6S, wire 15, front contact 16 of the track relay T⁵, wire 17, back contact 18 of the stick relay 6S, wire 19, front contact 20 of the track relay T⁴, wire 21, winding of the relay HD⁴, wire 22, resistance unit R⁴, wires 23, 24, 25, C, 25¹ and 26¹, to the mid-point of the battery. The closure of the circuit just traced will operate the relay HD⁴ to its left-hand dotted position, thereby placing the polar contact 31⁰ in a position to energize the caution lamp Y, instead of the green lamp G, thereby informing an approaching train that there is a train in the second block in advance, namely in the block J. 40

Let us now assume that the train in question, which is now occupying the block J, passes entirely out of this block J. For reasons already explained the home-distant relay HD⁶ will now be energized by current of negative polarity, and thus will move its neutral contact 43¹ to its attracted position, thereby breaking the stick circuit for the directional stick relay 6S, resulting in this relay 6S being deenergized and dropping its contact 14, as a result of which the normal circuit for the home-distant relay HD⁴ is again complete, resulting in the application of current of positive polarity, instead of current of negative polarity, to the relay HD⁴. As the train in question now passes beyond the second block in advance of the signal S⁶, this signal S⁶ will be returned to its normal clear position for reasons mentioned in connection with the signal S⁴, so that the signal system will again assume its normal condition, as shown in the drawing. 60

Attention is now directed to the resistance unit R⁴ included in series with the relay HD⁴. It will be noted that this resistance unit is normally short-circuited through a front contact 50 of the home-distant relay HD⁴. The purpose of this 7

resistance R^4 is to increase the time necessary for the relay HD^4 to assume its neutral armature attracted position. The advantage in having this home-distant relay HD^4 slow in picking up may be best explained by assuming a short train moving at high speed from right to left in the block I. As this train passes over the insulating joints 3, and if the track relay T^4 is slow to drop, as a shunted track relay is, and the track relay T^5 is quick to pick up as is usually the case, the home-distant relay HD^4 will be momentarily energized during this rapid passage of a short train over the insulating joints 3, but the provision of the resistance R^4 , which is now included in series with the relay HD^4 , the contact 50 being open, prevents the relay HD^4 from momentarily picking up, it being understood that momentary picking up of the relay HD^4 with the later de-energizing of the track relay T^4 might pick up the stick relay 4S at a time when the directional stick relay 4S should not pick up to energize HD^2 (not shown) to put signal S^2 (not shown) to caution, to thus allow an east-bound train, to run into the west-bound trains. In applicant's construction, however, the relay HD^4 is sufficiently slow to pick up to prevent such false picking up of the stick relay.

Applicant has thus proposed a system of single track signaling of the absolute-permissive-block type, which employs polar neutral relays which by their construction will not drop on momentary deenergization, and hence pole-changing, as of HD^6 will not drop HD^4 , etc., and these relays have been provided with an auxiliary resistance 35 R which causes these relays to be slow to pick up as is required in an absolute-permissive-block signaling system, thereby preventing accidental picking up of the opposing stick relay, and the

slow dropping function obtained is taken advantage of to afford picking up of the associated stick relay, all in a manner as already pointed out in the foregoing description, so that a comparatively simple system of absolute-permissive-block signaling employing a comparatively few relays, has been provided.

The above rather specific description of one form of the invention, has been given solely by way of illustration, and is not intended, in any manner whatsoever, in a limiting sense. Obviously, this invention can assume many different physical forms, and is susceptible of numerous modifications, and all such forms and modifications, are intended to be included by this invention, as come within the scope of the appended claim.

Having described my invention, I now claim:

In combination, a relay having slow pick up and slow release characteristics and including 20 an armature, a magnetic core and an operating winding on the core, an external resistance separate from the winding and connected in series with the winding to thereby produce slow pick up characteristics in the relay, means separate 25 from the winding and positioned on the core and constituting a low resistance short-circuited loop to produce slow release characteristics in the relay, and circuit means closing a relatively low resistance shunt across the external resistance 30 only upon the relay having picked up its armature, whereby the relay pick up current is less than the relay holding current, and the functioning of the said loop in producing slow release characteristics in the relay is unaffected by the 35 said external resistance.

JOSEPH E. WILLING.
